United States Patent Office.

ALEXANDER BECK, OF PHILADELPHIA, PENNSYLVANIA.

Design No. 4,481, dated November 22, 1870.

DESIGN FOR A CARPET-PATTERN.

The Schedule referred to in these Letters Patent and making part of the same.

I, ALEXANDER BECK, of Philadelphia, county of Philadelphia, State of Pennsylvania, have invented and produced a Design for a Carpet Pattern, of which the following is a specification.

The figure in the accompanying drawing represents sufficient of the pattern to illustrate my design, the principal features of which consist of the border A and body B, a portion only of the latter being shown in the drawings.

The border A consists of a stripe composed of groups or rows of figures, too clearly shown to need description, and the body of the pattern consists of figures of the peculiar shape and arranged in the peculiar manner represented, irrespective of the colors employed.

I claim—

1. The design for the border A, as described and shown.
2. The design for the body of the pattern as illustrated and described.
3. The design for the entire pattern shown, including both border and body.

In testimony whereof, I have signed my name to this specification in the presence of two subscribing witnesses.

ALEXANDER BECK.
